PRESS ATTACHMENT

Arthur C. Boettcher, Chicago, Ill.

Application February 4, 1942, Serial No. 429,549

1 Claim. (Cl. 77—63)

This invention relates to work tables for drill presses or the like, and to the means for supporting the work table. It is one of the objects of the present invention to provide a work table that may be secured to the column of a column type press and be arranged for easy adjustment vertically and horizontally by means of a number of hand wheels located adjacent one another in such positions that every hand wheel is accessible to the operator while the operator is operating the drill press.

It is one of the objects of the present invention to provide a simple work table support of the above mentioned character which may be readily and quickly applied to standard types of drill presses.

It is a still further object of the present invention to provide such a work table wherein the three adjusting hand wheels are each accessible to one hand of the operator while the other hand is being used to manipulate the drill.

For column mounting the unit of the present invention consists of a base or knee which slides over the tubular column of the press and is vertically raised or lowered by means of a hand wheel which turns a vertical lead screw in an adjustably fixed collar. Once the base has been adjusted to its desired position it may be locked in that position by two clamping levers.

A saddle plate or carriage is adjustably dove-tailed on the top of the base and is transversely adjustable by means of a crank and lead screw mounted in the base.

A work table is mounted in the saddle and moved longitudinally in dove-tailed guideways by means of a crank turning a lead screw in a bracket mounted on the saddle. Three T-slots are machined in the table surface for receiving clamping T-bolts, and two parallel machined V-slots in the top of the table provide a convenient method for holding round stock. The combination of V-slots for receiving the round stock to be worked upon, and the adjacent parallel T-slots for receiving the clamping bolts for holding the stock in place greatly facilitates the locking of the stock in position and constitutes an important part of the present invention.

The attainment of the above and further objects of the present invention will be apparent from the following specification taken in conjunction with the accompanying drawings forming a part thereof.

In the drawings:

Figure 1 is a perspective view of a conven-

tional type of drill press on which a table or bed of the present invention has been mounted;

Figure 2 is a top view of the table or bed of Figure 1;

5 Figure 3 is a sectional view taken along the line 3—3 of Figure 2 and looking in the direction of the arrows;

Figure 4 is a sectional view taken along the line 4—4 of Figure 2 and looking in the direction of the arrows; and

10 Figure 5 is a sectional view taken along the line 5—5 of Figure 3 and looking in the direction of the arrows.

15 In the accompanying drawings like reference numerals indicate like parts in the various figures.

Reference may now be had more particularly to Figure 1. At 11 I have shown a conventional drill press of the type to which the present invention is applicable. The drill press includes the usual base 2, a cylindrical upright column 3 and head 4. The head 4 includes the usual driving and speed changing mechanisms for driving a drill 6 at the desired speed, and the usual handle 7 for lowering the drill bit to the work. In the present instance the work is adapted to be clamped or otherwise secured upon a work table 10 that is adjustably mounted on the column 3. The work table includes a supporting

20 split ring 11 in the form of a cylindrical sleeve which embraces the upright column 3 and is keyed against rotation thereon by a bar key 12 that extends in a longitudinal slot in the column 3 and in a corresponding slot in the split ring 11.

25 The bar key thus retains the split ring against turning on the column while at the same time permitting longitudinal movement thereon. The split ring 11 extends for a substantial distance lengthwise of the column 3 and fits snugly

30 therearound so as to prevent any possible tilting of the base 16 which is integral with the split ring 11. Suitable hand tightened locking

35 bolts 17—17 extend through clamping ears 18—18 of the split ring 11. The bolts draw the ears together for locking the base in its vertically

40 adjusted position on the column 3 by clamping the split ring tightly around the column 3. For general working operations it is not necessary to lock the split ring about the column 3. The

45 split ring is supported in its adjusted position in a manner to be presently described.

50 A supporting or clamping ring 20, which is also in the form of a split ring, embraces the column 3 and has a keyway slot therein for receiving the bar key 12. The clamping ring

is positioned on the column 3 in any desired vertical position and is locked in place by a locking bolt 21 that extends through a pair of ears on the clamping ring 20 similar to the ears 18 of the ring 11. The clamping ring 20 is screw threaded to receive a vertical lead screw 22 that extends through the base 16 into and threads through the stationary collar or clamping ring 20. The lead screw is provided with a shoulder upon which an enlargement at the bottom of the base 16 rests, as may be seen from Figure 3. At the top of the lead screw there is provided a bevel gear 28 which meshes with a similar bevel gear 29 (Figs. 2 and 5) which is keyed to a hand operated shaft 31 that extends through the base 16 and is rotated by a hand wheel 32. Thus when the collar 20 is clamped in place and the clamping ring 11 is loose on the column 3 the base 16 may be adjusted vertically by turning the hand wheel 32 to turn the train of gearing including the vertical lead screw 22 that threads up and down in the clamping ring 20. It is apparent that due to the worm thread of the lead screw 22 a large amount of turning of the hand wheel 32 will result in a small amount of vertical movement of the base 16. There is thus provided a micromatic vertical adjusting means for raising and lowering the base 16 that ultimately supports the work on the work table 10.

A carriage 35 is mounted on the base 16 for horizontal movement towards and away from the column 3. To support the carriage the base 16 is provided with a flat top portion 36 including two guideways 37-37 the top surfaces of which are flat to constitute a support for the carriage and the side surfaces of which are beveled as indicated at 38 (Fig. 4), to fit into a correspondingly beveled groove at the base of the carriage 35. The carriage 35 has a downward projection 39 bolted thereto which extends into the space between the guideways 37, as may be seen in Figures 3 and 4. A lead screw 40 is journaled in the base 16 between the guideways 37-37 and threads into and through the projection 39. The lead screw is held against longitudinal movement in its bearing so that as the lead screw is rotated the projection 39 moves along the lead screw thus moving the carriage forward or backward along the guideways 37. The lead screw is provided with the usual hand operating wheel or crank 42 for turning the same. Thus upon turning the lead screw in one direction or the other the carriage is moved along the guideway towards or away from the column 3.

The carriage 35 slidably supports the work table 10. To this effect the top surface of the carriage is provided with supporting guideways 44 for supporting the table 10. The table 10 has tapered projections 43-45 that extend into a beveled trackway 46 that is formed in and extends transversely of the carriage 35 forming a dove-tail joint. A lead screw 46' threads through a projection 47 in the carriage 35 with an opposite end of the lead screw journaled in the table 10 against longitudinal movement with respect to the table. The lead screw 46' has a hand operated wheel or crank 47' secured thereto for turning the lead screw. Thus upon rotation of the lead screw the table 10 is shifted lengthwise in a direction at right angles to the guideways 37 of the carriage 35. It is thus possible to move the table crosswise of the carriage 35 and to move the table along the carriage 35 as well as to raise or lower the work table. There is thus provided a universal movement in three directions at right

angles to one another, the individual movements being effected by the three crank wheels 32, 42 and 47', all three of which are located adjacent one another so that an operator can reach and manipulate any two of them simultaneously. This is of importance since this will permit a very quick delicate adjustment of the work table with respect to the drill 6 so as to bring any desired point on the work table immediately beneath the drill 6.

Means is provided for locking the carriage 35 with respect to the base 16. This consists of a small screw 48 operated by a handle 48' which bears against a shim 49 between one of the guideways 37 and the carriage 35. In a like manner means is provided for locking the table 10 against crosswise movement with respect to the carriage 35, said means consisting of a screw 50 threaded through the carriage 35 and operated by a small handle 51 and pressing against a shim 52 between the carriage 35 and the work table 10, as may be seen in Figure 3. Suitable limiting stops 53-54 are carried by the forward edge of the table, slideable in a T-shaped slot 55 in the work table and locked in adjustable position by bolts 56 the heads of which are slideable in the T-shaped slots. Thus by setting the limiting stops in any desired position the limits of motion of the table 10 with respect to the carriage 35 may be fixed since the limiting stops abut against the carriage 35. Similar limiting stops may be provided for limiting the movement of the carriage 35 with respect to the base 16.

The lead screws 40 and 46' are supported in the same manner so that a description of the support for one of the screws will suffice for the other also. The support for the lead screw 40, illustrated in Figure 3, includes a knurled locking nut 57 threaded on a spacing and thrust bushing 58 which is externally threaded to receive the locking nut and also to receive a graduated dial 59 that bears against a sleeve 60 that is secured to the base 16 and has an index mark thereon cooperating with a rotatable dial. The lead screw 40 also has a thrust washer 61 on the end thereof opposite the sleeve 60 to hold the assembly together. With each revolution of the lead screw 40 the dial makes one turn and the carriage advances on the base a given amount. The calibrations on the dial will indicate fractions of that amount.

The top of the work table 10 is provided with longitudinally extending T-shaped slots 62-62 parallel to one another and separated by parallel V-shaped slots 63-64. The T-shaped slots are adapted to receive the heads of bolts the shanks of which extend upwardly above the table 10 and provide means for clamping the work to the table. The V-shaped slots constitute guideways for receiving the work, especially if the work is in the form of rods, pipes, tubes, or the like, which can lie in the V-slots 63 and 64. The V-slots 63 facilitate positioning of the work on the table and assure proper alignment of the work with respect to the two horizontal directions of motion of the work table under control of the lead screws 40 and 46'. Figure 3 shows a straight piece of round stock 65, such as a rod, positioned in one of the V-slots 64 and clamped in place by one or more bolts 66 the heads of which are in a T-slot and the shanks of which extend through a hole in a clamping plate 67 and are tightened by nuts 68. One end of the plate 67 bears against the work and the other end bears against a short removable spacer block 69 interposed between the

plate 67 and the work table 10. If desired, a plurality of spaced clamping plates may be used to lock the work in place, each block being held by a separate bolt 66.

It is apparent from the description thus far given that the present invention provides a simple attachment that may be secured to an existing press and will permit an adjustment of the work table vertically as desired, and an additional adjustment horizontally in each of two directions at right angles to one another. It is also apparent that the operating handles 42 and 47' are sufficiently close together so that an operator standing in front of the press in position to operate the press handle 7 can grasp both handles 42 and 47' simultaneously, or either one of those two and the handle 33, or may grasp any one of those three handles with one hand while operating the drill handle 7 to raise or lower the drill. This gives a flexibility of operation hitherto unattainable in low cost machines.

In compliance with the requirements of the patent statutes I have here shown and described a preferred embodiment of my invention. It is, however, to be understood that the invention is not limited to the precise construction here shown, the same being merely illustrative of the principles of the invention.

What I consider new and desired to secure by Letters Patent is:

A press attachment comprising a collar adapted to embrace an upright main column of a press

and movable vertically thereon, means for securely clamping the collar in place in any position vertically along the column, a base above the collar and adapted to embrace the same main column and slide vertically thereon, a vertical lead screw connection between the base and the collar for shifting the base vertically towards and away from the collar, means including a horizontal rotatable operating shaft and gearing connecting the shaft with the screw for turning the lead screw to impart the vertical movement to the base, a carriage slidably mounted on said base, means including a rotatable operating shaft extending from the front towards the rear of said carriage for imparting a sliding movement to the carriage, a work table on said carriage and movable thereon in a direction at right angles to the direction of movement of the carriage on the base, means including a rotatable operating shaft extending from one transverse side of the work table towards the opposite side thereof for imparting movement to the table with respect to the carriage, said two last mentioned shafts being horizontal and at right angles to one another and both within simultaneous reach of a press operator standing in front of said attachment, and said first operating shaft terminating between the other two operating shafts whereby an operator can operate any two of the shafts simultaneously while the operator is in his press-operating position.

ARTHUR C. BOETTCHER.
